(57) **CLAIM**

The ornamental design for a set of tail lights, as shown and described.

DESCRIPTION

The file of this patent contains a least one drawing/photograph executed in color. Copies of this patent with color drawing(s) will be provided by the Office upon request and payment of the necessary fee.

FIG. 1 is a front view of a set of tail lights of our present design;

FIG. 2 is a left side view thereof;

FIG. 3 is a right side view thereof;

FIG. 4 is a top view thereof;

FIG. 5 is a bottom view thereof;

FIG. 6 is a front, left perspective view thereof.

Portions of the automobile shown in a lighter, "washed-out" appearance form no part of the claimed design, other than a positioning relative to the claimed set of tail lights.
